UNITED STATES PATENT OFFICE

MANUEL ABASCAL, OF SAN FRANCISCO, CALIFORNIA

WIRE-TIGHTENING DEVICE

Application filed December 9, 1925, Serial No. 74,344. Renewed August 3, 1929.

This invention relates to a wire tightening device for the purpose of twisting the wires used in holding concrete centering in place, and an object of the invention is to provide means whereby the twist may be easily made while the wire is thereupon pulled taut and the twist then finished.

Another object of the invention is to provide means whereby the jaws will securely hold the wire ends and also be provided with a cutter for cutting the wires wherever necessary.

Other objects of the invention will appear as the description proceeds.

15 An embodiment of the invention is shown in the accompanying drawings in which the same reference numeral is applied to the same portion throughout the several figures of the drawings and of which there may be modifications.

Figure 1 is a side elevation of the wire tightening device.

Figure 2 is a plan view of the wire tightening device.

25 Figure 3 shows the way the wire tightening device is used to tighten the wires showing the wire tightening device in side elevation.

Figure 4 is a side elevation of the jaws on a 30 larger scale.

Figure 5 is a view of a section of the centering showing the application of the wire thereto.

35 This wire tightening device consists of a pair of crossed handles 1 and 2, secured together by a pivot 3, the jaws 4 and 5 having transverse ribs 6 and 7 and cutting edges 8 and 9.

40 The ribs 6 and 7 are so formed as to give the wire ends a crimp which will hold the wires tightly, and when so held and partly twisted together the depending lug 10 on the jaw 5 is used as a lever to tighten the wire 45 and then to twist the ends together close up to the centering.

Figure 5 shows a portion of the framework of the centering wired up tight, the numerals 50 12 and 13 indicating the inside facing, and 14 and 15 the studding and stringers for holding

the centering together, the wire 18 having its ends twisted together at 19.

Figure 3 shows the manner of application of the wire 20, as well as the manner of tightening it.

In use the wire is placed around the centering, the ends are then gripped by the pliers and twisted together slightly, whereupon the workman then uses the lug 10 as a fulcrum and tightens the wire loop by bearing down 60 on the handles 1 and 2. When the wire has been pulled tight the twist is completed.

The depending lug 10 projects beyond the end of the jaws 4 and 5 to give room for the twist formed in the wire between the end 65 of the jaws and the studding.

What I claim is as follows, but modifications may be made in carrying out the invention shown in the drawings and in the above particularly described form thereof, 70 within the purview of the invention.

A wire tightening device comprising a pair of pivotally connected crossed handles having upper and lower gripping jaws, the lower jaw projecting downwardly and forwardly at an 75 angle from the meeting point of said jaws, and having a right angle forward projection at the bottom thereof.
